Application August 9, 1952, Serial No. 303,551

14 Claims. (Cl. 269—219)

The present invention relates to an improved magnetic separator for dry granular or powdered minerals wherein permanent magnets are used in place of the usual electromagnets for separating magnetic particles from the minerals.

One object of the invention is to provide an improved magnetic separator which is comparatively simple and compact in construction, which is efficient and economical in operation, and which can be manufactured at considerably less cost, yet perform much of the magnetic separation required by those types of magnetic separators which employ direct current in electromagnets thereof, and therefore usually require current converters or heavy rectifiers as most current now supplied is of the alternating current type.

Another object is to provide a magnetic separator in which the magnetism produced by permanent magnets is regulated by a shunting arrangement in which the distance of the shunt from the magnet pole pieces is adjustable for this purpose.

Still another object is to provide a permanent magnet equipped magnetic separator with extensions which cooperate with the magnets for producing an arrangement of progressively greater magnetic attraction in a series of rollers over which the minerals are fed by a chute and baffle arrangement of novel construction.

Still another object is to provide a chute arrangement which produces smooth flow of the minerals to the roller and wherein the chute and a knife edge carried thereby may be adjusted in proper relation to its cooperating rotor for separating the magnetic particles from non-magnetic particles.

A further object is to provide a chute arrangement wherein the chute may be adjusted as to angle and to provide a knife edge arrangement supported on the chute wherein the knife edge may be adjusted along the chute for changing its position with respect to the rotor.

Still a further object is to provide a pole-piece arrangement for the permanent magnets with a novel mounting means for the magnets with respect to the pole pieces, and wherein the arrangement is capable of adjustment of the pole piece, relative to the rotor in a comparatively simple manner to permit adjustment of the air gap between the two.

Still a further object is to provide bearing housings of non-magnetic material in which the shafts for the rotors are journaled, which housings therefore provide a non-magnetic support for the pole pieces and a support for the front part of a chute assembly which locates the discharge edge of the chute in the exact position needed for smooth feeding of the material to the rotor no matter what angle to which the chute is adjusted.

An additional object is to provide in a magnetic separator, a rotor provided with a grooved surface and plastic material hardened in the groove to act as a non-magnetic insert in the surface of the rotor to provide convergence of the magnetic field toward the rotor.

With these and other objects in view, my invention

consists in the construction, arrangement and combination of the various parts of my magnetic separator, whereby the objects contemplated are attained, as herein-after more fully set forth, pointed out in my claims and illustrated in the accompanying drawings, wherein:

Figure 1 is a side elevation of a magnetic separator embodying my present invention.

Figure 2 is an enlarged angular plan view thereof as taken from the line 2—2 adjacent Figure 1 to show the rotor, magnet, shunt and magnet extensions of the separator.

Figure 3 is a sectional view on the line 3—3 of Figure 2.

Figure 3a is a fragmentary view similar to a portion of Figure 3 to show an adjustment feature for the air gap between a pole piece and a rotor of my magnetic separator.

Figure 4 is an enlarged sectional view on the line 4—4 of Figure 3 to show a magnetic shunt and the adjustment mechanism therefor.

Figure 5 is an enlarged sectional view on the line 5—5 of Figure 3 to show a cross section of the rotor surface.

Figure 6 is a sectional view on the line 6—6 of Figure 3 and shows the action of the separator in operation; and Figures 7 and 8 are detail sectional views on the lines 25 7—7 and 8—8 respectively of Figure 6.

On the accompanying drawings I have used the reference numeral 10 to indicate skids on which my magnetic separator is mounted. A frame is provided consisting of horizontal frame members 12 and 14 and vertical frame members 16 and 18, which may be suitably connected together as by welding.

Uprights 20 are mounted on the frame members 14 and support a hopper 22 and a vibratory chute 24 for feeding the granulated or powdered minerals as will hereinafter be described. The vibratory chute forms no part of my present invention and accordingly will not be described in detail.

A pair of supporting bars 26 are mounted at an angle on the frame members 12, 14 and 16, and are connected together by a supporting plate 28. Six bearing members 30 are mounted in bearing housings 31 and rotatably support three rotor shafts 32 on which are mounted three rotors 34. Each rotor 34 is formed of magnetic material and its surface is provided with a spiral groove 36 in the form of an isosceles trapezoidal thread (see Figure 5) and this thread is filled with a plastic material 38, preferably one which hardens quickly by the use of a catalyst so that the rotor may be manufactured in a minimum of time. The plastic material, of course, is non-magnetic and being in the form of an insert in the surface of the rotor, it provides for an increase in the magnetic pull toward the rotor when compared with a rotor that does not have such an insert.

For driving the rotors 34, I provide pulleys 35 belted together by belts 49 and 51. A pulley 39 is mounted on the shaft of the upper rotor 34 and is operably connected by a belt 37 to a pulley 41 on a speed reducer 45. The speed reducer is driven by a motor 47.

It is preferable to provide a relatively strong magnetic field adjacent the lower rotor 34 in Figure 1, a magnetic field of less force adjacent the middle rotor, and a magnetic field of still less force adjacent the upper rotor 34. I accomplish this with an inexpensive arrangement which will now be described.

Three pole pieces 40 of magnetic material such as soft steel are provided for the three rotors 34. They are secured to the bearing housings 31 by screws 42 threaded in the housings and set screws 43 are threaded in the pole pieces (as best shown in Figure 3a) to permit of adjustment as will hereinafter be described. Adjacent the lower two pole pieces 40, I provide bars 44 as shown particularly in Figures 2, 4 and 6. Magnets 54 have their ends

located against the faces of the bars 44, and are retained in position with respect to the bars by retainer bars 48 secured to the upper and lower edges of the bars 44 by screws 52. The retainer bars 48 are notched at 50 to locate the magnets 54 in properly spaced relation along the bars 44. The magnets are stippled in both elevation and cross section throughout the drawings to distinguish them from other parts of the separator.

The entire assembly of the lower two pole pieces 40, the bars 44, and the magnets 54 is retained in the assembled position by means of tie rods 56 extending through the pole pieces and the bars 44 and provided with nuts 58 for adjustment purposes. The outer nuts are tightened for bringing all parts into snug engagement and then the inner nuts are tightened to serve as lock nuts and retain the parts assembled without relative movement.

Magnetic extension bars 60 are mounted on a pair of extension mounting bars 62 of magnetic material as shown in Figure 2 by means of screws 64, and the lower bar 62 is secured to the middle pole piece 40 by means of the upper nuts 58 on the tie rods 56 as illustrated. The upper extension mounting bar 62 is secured to the upper pole piece 40 by bolts 66.

The arrangement just disclosed provides a lower air gap A in Figure 6 between the lower rotor 34 and the lower pole piece 40 of maximum magnetic strength and an upper air gap B between the middle pole piece 40 and the middle rotor 34 of somewhat less strength because part of the magnetism is carried off through the magnetic extension bars 60 to provide a similar magnetic air gap (the uppermost of the three in Figure 1) between the upper pole piece and the upper rotor 34 which is even weaker than the gap B. Thus there is a progressively stronger magnetic field acting on the mineral or other material being magnetically separated as the material passes through the machine.

The magnetic effect of the magnets 54 may be reduced by means of magnetic shunts 68 in the form of plates of magnetic material which short circuit part of the magnetism from the lower and middle pole pieces 40. The plates 68 are each mounted by one upper set screw 70 and two lower set screws 72 which provide a three-point support. As shown in Figure 4, this provides an air gap C between 68 and the retainer bars 48 and the gap may be adjusted by rotation of the set screws 70 and 72. The set screws are threaded in the magnetic shunts 68 and due to the magnetic attraction of the pole pieces 40 with respect to the shunts 68, the pole pieces being energized of course by the magnets 54, the magnetic shunts remain in the position illustrated by merely providing reduced ends 74 on the set screws 70 and 72 to enter sockets 76 of the pole pieces 40.

Above each rotor 34 I provide a chute assembly 78. The chute assembly comprises a primary chute 80, a secondary chute 82, a divider or "knife edge" 84 on the primary chute, and a baffle 86. A slot 88 is provided in the primary chute 80 adjacent the baffle and a chute cover 90 is provided for the chute 78 as best shown in Figure 6.

The chute assembly 78 is mounted on a pair of mounting tracks 92 pivoted at 94 to the bearing housings 31. Each mounting track 92 is provided with an adjusting rod 96 pivoted thereto, which extends through the supporting plate 28 and the supporting bar 26 as shown in Figure 8. The bar is provided with a set screw 98 for the purpose of retaining the adjusting rod in a desired adjusted position.

A tailings chute 100 is provided as shown in Figure 6 below each of the rotors 34, and it will be noted by reference to Figure 1 that one of the chute assemblies 78 is also provided below the lower rotor 34.

The mounting track 92, as shown in Figure 8, is grooved as at 102 to receive a slide 106. The chute assembly 78 is supported on supporting bars 104 and is connected by clamp screws 108 to the slides 106 so that the primary chute 80 and its divider 84 can be adjusted up-

wardly along the mounting tracks 92 as shown by dotted lines in Figure 6, and its angle may also be adjusted as likewise shown by the dotted line position of the mounting tracks 92.

5 In Figure 6 I have indicated in circles the north and south poles of the magnets 54 by the characters N and S encircled. The resultant north and south poles for the pole pieces 40 and the rotors 34 are similarly indicated.

10

Practical operation

In the operation of my magnetic separator, reference is made particularly to Figures 1 and 6. The mineral from which magnetic particles are to be separated is deposited in the hopper 22 and flows into the vibratory chute 24. From there it flows over the top edge of the divider 84 shown in section in Figure 1 and into the uppermost primary trough 80 down which it slides in the manner illustrated in Figure 6. It attains a certain speed of flow and the angle of the chute assembly 78 is adjusted so that the flow is entirely free. However, free flow is too fast for proper magnetic separation in the air gap between the upper rotor 34 and the upper pole piece 40. I, therefore, provide the baffle 86 just below the slot 88, and the material strikes the baffle thus arresting its flow and it thereupon flows through the slot and into the secondary chute 82 where the flow is short so that the material does not have a chance to attain too much momentum. Just the right momentum can be regulated by changing the angle of the chute assembly 78 at the set screws 98.

35 The material to be separated flows over the first or upper rotor 34 and part of the magnetic material is separated out; whereas the rest of the material flows on to the middle rotor 34 and more of the magnetic material is removed from the flowing material as will now be described in connection with Figure 6. After this description of Figure 6, it will be obvious how separation takes place at the upper rotor 34 in Figure 1 in a manner similar to the middle rotor 34 (which is the upper one shown in Figure 6).

40 The non-magnetic material and some slight portion of the magnetic material will fall in a trajectory indicated at 110. The curvature of the trajectory depends on the speed of the material as it comes off the rotor. Assuming a trajectory 110 as illustrated in Figure 6, the material referred to goes to the right of the divider 84 as illustrated so as to fall into the primary chute 80.

45 A trajectory 112 is shown for the magnetic particles which tend to follow the surface of the rotor 34 and the trajectory 112 is therefore separated from the trajectory 110 and falls to the left of the divider 84. This magnetic material falling along the trajectory 112 lands in the tailings chute 100 and flows out as illustrated.

50 If it is desirable to increase the angle of the chute assembly 78 to speed up the flow of the material yet retain the same speed of rotation of the rotors 34, the mounting tracks 92 may be adjusted to the dash line position shown in Figure 6 and the primary chute assembly adjusted upwardly along these tracks so that the divider 84 is at a position such as 84a and still substantially half-way between the trajectories 110 and 112. Likewise the angle of the chute assembly and the position of the divider may be adjusted for a faster or slower rotating rotor and for the character of the material being passed through the magnetic separator.

55 A small percentage of the magnetic material is separated in a trajectory similar to 112 just described from the upper rotor 34, additional material is separated as just described in connection with Figure 6 and further magnetic material is separated as at 112a from the material in the trajectory 110a at the lower rotor 34 in Figures 1 and 6. Finally the material issues as at 110b in Figure 1 and contains very little or no magnetic material. By having the maximum magnetic field at A in Figure 6, less magnetic field at B, and still less between

the upper pole piece 40 and the upper rotor 34 as already described, the separation of magnetic particles is progressive and is accomplished with the greatest efficiency.

When operating on material of such character that greater magnetic influence is desirable from the magnets 54, the shunts 68 can be removed. On the other hand, when it is desirable to reduce the magnetism, this may be accomplished by short-circuiting some of it by adjusting the shunts 68 closer to the retainer bars 48 for reducing the effect of the magnets 54 on the pole pieces 40. Also the magnetic gap shown at B for instance in Figure 3, can be increased in dimension by proper adjustment of the screws 42 and 43 (see Figure 3a) between the pole piece 40 and the bearing housings 31. This would increase the spacing as to the dimension B' in Figure 3.

As already described, the angle of the chute assembly and the position of the divider 84 may be readily adjusted to take care of different speeds of operation and different materials being worked upon. It has been found that a rotor surface, which is not continuous but is interrupted with non-metallic portions is superior to one that is formed entirely of magnetic material and I provide a relatively economical arrangement for manufacturing such rotors as described above in connection with Figure 5. By having the rotor surface interrupted by grooves filled with non-magnetic material such as a hardened plastic, I provide a converging magnetic field between the ungrooved portions of the rotor and the adjacent pole piece.

While in the foregoing description I have made reference to three rotors 34, the number may be increased or decreased depending on the requirements. My magnetizing arrangement for the pole piece 40 as well as the shunt 68 used in connection therewith and the chute assembly disclosed may in fact be used in connection with a single rotor where only one is sufficient for the magnetic separation needed.

From the foregoing specification it will be obvious that I have provided a magnetic separator which will accomplish the objects set forth in my specification and yet is economical to produce since it uses permanent magnets, thus eliminating the necessity of providing electric current for electromagnets and the necessary equipment for changing alternating current to direct current where required.

Some changes may be made in the construction and arrangement of the parts of my magnetic separator without departing from the real spirit and purpose of my invention, and it is my intention to cover by my claims any modified forms of structure or use of mechanical equivalents which may be reasonably included within their scope.

I claim as my invention:

1. A magnetic separator of the character disclosed comprising, a frame structure, a base plate supported thereby, a plurality of spaced rotors rotatably mounted thereon and having their axes in a plane substantially inclined from the vertical, means for magnetizing said rotors comprising permanent magnets extending substantially parallel to said plane from rotor to rotor, pole pieces at the ends of said magnets to be magnetized thereby, said pole pieces being spaced from said rotors to provide magnetic air gaps through which material to be separated may flow, chute means also substantially parallel to said plane for feeding material to be separated through said magnetic air gaps, dividing means at the discharge of each rotor for dividing the magnetic particles separated from said material, said chute means being adjustable as to inclination and said dividing means being adjustable relative to said chute means.

2. In a magnetic separator, a frame structure, a base plate supported thereby, a plurality of spaced rotors rotatably mounted thereon, means for magnetizing said rotors comprising permanent magnets extending from rotor

to rotor, pole pieces at the ends of said magnets to be magnetized thereby, magnetic extensions from one of said pole pieces to adjacent another of said rotors, a pole piece at the outer ends of said magnetic extensions to be magnetized thereby, said pole pieces terminating adjacent but spaced from said rotors to provide magnetic air gaps through which material to be separated may flow, a chute assembly for delivering material to be separated to each of said rotors, said chute assembly being pivotally mounted adjacent the rotor and adjustable about the pivotal connection, a divider carried by each chute assembly and adjustable along the chute assembly, said chute assembly including a primary chute leading from said divider, a secondary chute below said primary chute and a baffle adjacent the discharge end of said primary chute to slow down the flow of the material and change the direction of its course into the secondary chute, said secondary chute being comparatively short to minimize the attainment of velocity of the material as it flows therewith.

3. In a magnetic separator, a frame structure, a base plate supported thereby, a plurality of spaced rotors rotatably mounted thereon, means for magnetizing said rotors including pole pieces spaced from said rotors to provide magnetic air gaps through which material to be separated may flow, a chute assembly for delivering material to be separated to each of said rotors in tandem, each of said chute assemblies being pivotally mounted adjacent the rotor to which it delivers material and adjustable about the pivotal connection, and a divider carried by each chute assembly and adjustable along the chute assembly toward the rotor from which it receives material.

4. In a magnetic separator, a frame structure, a base plate supported thereby, a plurality of spaced rotors rotatably mounted thereon, means for magnetizing said rotors including pole pieces spaced from said rotors to provide magnetic air gaps through which material to be separated may flow, a chute assembly for delivering material to be separated to each of said rotors in tandem, each of said chute assemblies being pivotally mounted adjacent the rotor to which it delivers material and adjustable about the pivotal connection, a divider carried by each chute assembly and adjustable along the chute assembly toward the rotor from which it receives material, said chute assembly including a primary chute leading from said divider, a secondary chute below said primary chute and a baffle beyond the discharge end of the primary chute to slow down the flow of the material and change the direction of its course into the second chute, said baffle being close to the discharge end of said secondary chute.

5. In a magnetic separator, a frame structure, a base plate supported thereby, a plurality of spaced rotors thereon, means for magnetizing said rotors comprising permanent magnets, pole pieces spaced from said rotors and magnetized by said magnets to provide magnetic air gaps through which the material to be separated flows, a chute assembly for delivering material to each of said rotors, said chute assembly being pivotally mounted adjacent the rotor to which it delivers material and adjustable about its pivotal mounting, a divider carried by each chute assembly and adjustable along the chute assembly toward the rotor from which it receives material, said chute assembly including a primary chute leading from said divider, a secondary chute below said primary chute and a baffle adjacent the discharge end of the primary chute to slow down the flow of the material and change its direction as it flows into the secondary chute, said secondary chute being relatively steep to insure free flow of the material and being comparatively short to minimize the attainment of velocity by the material as it flows therewith, a shunt for said magnets and means for adjusting said shunt toward said magnets to reduce the magnetism in said magnetic air gaps.

6. In a magnetic separator, a frame structure, a base plate supported thereby, a plurality of spaced rotors rotatably mounted thereon, means for magnetizing said rotors comprising permanent magnets, pole pieces extending from the poles thereof to positions adjacent said rotors to provide magnetic air gaps through which the material to be separated flows, a chute assembly for delivering material to each of said rotors, said chute assembly being pivotally mounted adjacent the rotor and adjustable about its pivotal connection, a divider carried by each chute assembly and adjustable along the chute assembly, a shunt for said magnets, and means for adjusting said shunt toward said magnets to reduce the magnetism in said magnetic air gaps.

7. In a magnetic separator, a frame structure, a base plate supported thereby, a plurality of spaced rotors thereon, means for magnetizing said rotors comprising permanent magnets and pole pieces spaced from said rotors to provide magnetic air gaps through which the material to be separated flows, chute means for feeding material to be separated through said magnetic air gaps, dividing means at the discharge of each rotor for dividing the magnetic particles separated from said material, a shunt for said magnets, means for adjusting said shunt toward said magnets to reduce the magnetism, means for mounting said magnets on said pole pieces comprising tie rods connecting said pole pieces together and clamping said magnets between them, and retainer bars along opposite edges of the pole pieces to retain said magnets located in relation thereto.

8. In a magnetic separator, a frame, a base plate supported thereby, a plurality of spaced rotors mounted thereon, means for magnetizing said rotors comprising permanent magnets and pole pieces spaced from said rotors to provide magnetic air gaps, chute means for feeding material to be separated through said magnetic air gaps, means for mounting said magnets on said pole pieces comprising tie rods extending substantially parallel to said magnets, connecting said pole pieces together and clamping said magnets between them, and retainer bars along opposite edges of the pole pieces to retain said magnets located relative to said pole pieces.

9. In a magnetic separator, a frame, a base plate supported thereby, a plurality of spaced rotors thereon, means for magnetizing said rotors comprising permanent magnets, pole pieces spaced from said rotors to provide magnetic air gaps through which the material to be separated flows, said pole pieces being magnetized by said magnets, a shunt for said magnets, means for adjusting said shunt toward said magnets, and means for mounting said magnets on said pole pieces comprising tie rods extending substantially parallel to said magnets, connecting said pole pieces together and clamping the ends of said magnets against said pole pieces.

10. In a magnetic separator, a frame structure, a base plate supported thereby, a plurality of spaced rotors mounted for rotation thereon, means for magnetizing said rotors comprising permanent magnets and pole pieces spaced from said rotors to provide magnetic air gaps through which the material to be separated flows, a chute assembly for delivering material to each of said rotors, said chute assembly being pivotally mounted adjacent the rotor and adjustable about its pivotal mounting, a divider carried by each chute assembly and adjustable therewith, said chute assembly including a primary chute leading from said divider, a secondary chute below said primary chute and a baffle adjacent the discharge end of the primary chute to slow down the flow of the material and change its direction as it flows into the secondary chute, a shunt for said magnets, means for adjusting said shunt toward said magnets to reduce the magnetism in said magnetic air gaps, and means for mounting said magnets on said pole pieces comprising tie rods connecting said pole pieces together with said magnets interposed between them.

11. In a magnetic separator, a frame structure, a base plate supported thereby, a plurality of spaced rotors rotatably mounted thereon, means for magnetizing said rotors comprising permanent magnets extending from rotor to rotor, pole pieces at the ends of said magnets to be magnetized thereby, magnetic extensions from one of said pole pieces to adjacent another of said rotors, a pole piece at the outer ends of said magnetic extensions to be magnetized thereby, said pole pieces being spaced from said rotors to provide magnetic air gaps through which material to be separated may flow, a chute assembly for delivering material to be separated to each of said rotors, said chute assembly being pivotally mounted adjacent the rotor to which it delivers material and adjustable about the pivotal mounting, a divider carried by each chute assembly and adjustable along the chute assembly toward the rotor from which it receives material, said chute assembly including a primary chute leading from said divider, a secondary chute below said primary chute, and a baffle beyond the discharge end of the primary chute to slow down the flow of the material and change the direction of its course into the secondary chute, said baffle delivering the material close to the discharge end of said secondary chute.

12. In a magnetic separator, a frame structure, a base plate supported thereby, a plurality of spaced rotors rotatably mounted thereon, means for magnetizing said rotors comprising permanent magnets extending from rotor to rotor, pole pieces at the ends of said magnets to be magnetized thereby, said pole pieces being spaced from said rotors to provide magnetic air gaps through which material to be separated may flow, a chute assembly for delivering material to be separated to each of said rotors, a divider carried by each chute assembly and adjustable along the chute assembly, said chute assembly including a primary chute leading from said divider, a secondary chute below said primary chute, and a baffle beyond the discharge end of the primary chute to slow down the flow of the material and change the direction of its course into the secondary chute, said baffle delivering the material close to the discharge end of said secondary chute.

13. In a magnetic separator, a frame structure, a base plate supported thereby, a rotor journalled thereon, means for magnetizing said rotor comprising permanent magnets and a pole piece at the ends of said magnets to be magnetized thereby, said pole piece being spaced from said rotor to provide a magnetic air gap through which material to be separated may flow, chute means for feeding material to be separated through said magnetic air gap to the intake side of said rotor, dividing means at the discharge side of said rotor for dividing the magnetic particles separated from said material, a shunt for said magnets, and means for mounting said shunt in spaced relation to said magnets comprising set screws threaded therethrough and entering sockets in said pole piece, said set screws, when adjusted inwardly relative to said shunt, permitting it to move, due to the magnetic attraction thereof by said pole piece, toward said magnets to reduce their magnetic effect on said pole piece and said rotor.

14. A magnetic separator of the character disclosed comprising a frame structure, a base plate supported thereby, bearing housings mounted thereon, a rotor rotatably journalled in said bearing housings, means for magnetizing said rotor comprising permanent magnets and a pole piece at the ends of said magnets to be magnetized thereby, said pole piece being spaced from said rotor to provide a magnetic air gap through which material to be separated may flow, chute means for feeding material to be separated through said magnetic air gap, said chute means being pivoted adjacent its discharge end to said bearing housings, and means for adjusting its inclination, the discharge end of said chute remaining in

65

substantially the same relation to the rotor to which it delivers material in all positions of chute adjustment.
